CLAIM

The ornamental design for a card PC, as shown and described.

DESCRIPTION

FIG. 1 is a perspective view of a card PC showing our new design with an environmental docking station;

FIG. 2 is a top perspective view of the device in FIG. 1;

FIG. 3 is a bottom perspective view of the device in FIG. 1;

FIG. 4 is a top planar view of the device in FIG. 1;

FIG. 5 is a bottom planar view of the device in FIG. 1;

FIG. 6 is a right side planar view of the device in FIG. 1;

FIG. 7 is a left side planar view of the device in FIG. 1;

FIG. 8 is a front planar view of the device in FIG. 1; and,

FIG. 9 is a back planar view of the device in FIG. 1. The bracket and the number **10** are not part of the claim.FIG. 10 is an enlarged view of the back planar surface shown at section "**10**" in FIG. 9. The two large zig-zag lines truncating the left and right sides of the enlarged section "**10**" form no part of the claim.

Broken lines in the drawings are included for the purpose of illustrating an environment and form no part of the claimed design.
